(57) **CLAIM**

The ornamental design for a rechargeable electronic cigarette, as shown and described.

DESCRIPTION

FIG. 1 is a front view of a rechargeable electronic cigarette in accordance with an embodiment of the claimed invention; FIG. 2 is a front view of an upper portion of the rechargeable electronic cigarette of FIG. 1;

FIG. 3 is a front view of a bottom portion of the rechargeable electronic cigarette of FIG. 1;

FIG. 4 is a bottom view of the upper portion of the rechargeable electronic cigarette of FIG. 2;

FIG. 5 is a top view of the bottom portion of the rechargeable electronic cigarette of FIG. 3;

FIG. 6 is a top view of the rechargeable electronic cigarette of FIG. 1;

FIG. 7 is a bottom view of the rechargeable electronic cigarette of FIG. 1.

FIG. 8 is a side view of the rechargeable electronic cigarette of FIG. 1;

FIG. 9 is a side view of an upper portion of the rechargeable electronic cigarette of FIG. 2;

FIG. 10 is a side view of a bottom portion of the rechargeable electronic cigarette of FIG. 3;

FIG. 11 is a back perspective view of the electronic cigarette of FIG. 1;

FIG. 12 is a back perspective view of the upper portion of the rechargeable electronic cigarette of FIG. 2; and, FIG. 13 is a back perspective view of the bottom portion of the rechargeable electronic cigarette of FIG. 3.

The broken lines shown in FIGS. 1-9 depict portions of the rechargeable electronic cigarette that form no part of the claimed design.
